MOBILE VACUUM CLEANER HAVING A HOSE ADAPTED TO BE USED AS A PUSHING OR PULLING MEANS THEREFOR

John C. Shalvay, Fairfield, and Paul O. Rawson, Jr., Trumbull, Conn., assignors to General Electric Company, a corporation of New York

Application December 21, 1953, Serial No. 399,271

5 Claims. (Cl. 15—323)

The present invention relates to vacuum cleaners of the type comprising a casing in the form of a drum or cylinder supported at opposite ends on wheels, the drum or cylinder, in its side wall, being provided with walls which define a suction inlet for the vacuum cleaner hose. In such cleaners the hose comprises a flexible section formed of a length of flexible tube having at one end a connector which fits in the suction inlet to connect the hose to the cleaner, and a rigid section, termed usually a wand, suitably connected to the outer end of the flexible section. The free or outer end of the wand is arranged to have different cleaning tools attached thereto, the wand forming a handle for a cleaning tool for moving it over the surface to be cleaned.

A vacuum cleaner of this type has the advantage of being mobile, it being easily moved across a floor by the hose when being used. However, since the hose section which is connected to the cleaner casing is flexible, it becomes awkward and inconvenient to move the cleaner from one room to another for example, or up and down stairs by the suction hose. Also, it is awkward because of the length of the hose.

The object of the present invention is to provide an improved construction and arrangement whereby the free or tool end of the wand of a suction hose can be connected to the vacuum cleaner casing whereby it forms a handle for use in moving the cleaner on its wheels from one place to another, for example, from one room to another, or up and down stairs, and for supporting the cleaner against a wall for storing, which is simple in structure, easy to use and capable of being embodied in a vacuum cleaner at little additional cost.

According to our invention we provide in connection with a vacuum cleaner of the above-referred to type, a projecting handle which is located directly adjacent to the connection of the hose to the vacuum cleaner casing; and beneath the handle, between it and the hose connection, we provide walls which form a pocket in which may be positioned the end of the wand to which the cleaning tools are attached whereby the wand may be used as a rigid handle for moving the cleaner, the other end of the hose being at the same time attached to the cleaner so that the hose as a whole is carried along. In other words, both ends of the hose are attached to the cleaner, thus forming the hose into a loop, and the wand is used as a handle. The underside of the handle is shaped to form the top wall of the pocket and it is provided with a transversely extending groove in which the latch nose on the wand end which serves to fasten cleaning tools to the wand end engages to fasten the wand end in the pocket. Preferably, the arrangement is such that the latch nose may be released from the groove by a turning of the wand.

For a consideration of what we believe to be novel and our invention, attention is directed to the following specification and to the claims appended thereto.

In the drawing, Figs. 1, 2 and 3 are views illustrating the use of the invention.

Fig. 4 is a perspective view of a vacuum cleaner embodying the invention.

Fig. 5 is a side view partly broken away.

2

Fig. 6 is a detail sectional view taken on line 6—6, Fig. 5.

Referring to the drawing, 1 indicates the casing of a vacuum cleaner which is in the form of a drum or cylinder. At its two ends the casing is supported on wheels 2 and 3 suitably attached to it, the cleaner being adapted to be moved around on the wheels. On the side of casing 1 are walls which define the suction inlet 4 of the cleaner, it embodying means whereby the one end of a suction hose may be fastened therein. In the casing are the usual motor driven suction fan and dust bag, and at a suitable point is the air discharge opening. Such parts form no part of the present invention and for this reason they have not been illustrated.

The suction hose comprises a flexible tube section 5 having at one end a connector 6 for connecting the suction hose to the suction inlet. Connector 6 may be made of metal or other suitable rigid material. It is of a diameter to fit into the suction inlet and may be provided with suitable means (not shown) for detachably locking it in the inlet. The locking means may be of any suitable structure and since its specific structure forms no part of our invention and such locking means are known, it has not been illustrated.

Attached to the other end of flexible hose section 5 by suitable means is a rigid tube section 8, termed usually a wand, formed from metal tubing for example. Preferably the connection between the flexible hose section, and wand is formed by curved, rigid, coupling tube 9, which is permanently swiveled to the free end of the hose section and adapted to be releasably coupled to wand 8 in a conventional manner. If desired, cleaning tools may be attached directly to the tube 9 for certain cleaning operations. When connected to the flexible hose, wand 8 is normally used as a handle for several cleaning tools, its free end being provided with latch means for detachably connecting tools to it, and it may be provided with a curved end as best shown in Fig. 2 so that when a cleaning tool is attached to its said end, its other end is at a convenient height and the wand is at a convenient angle for moving the cleaning tool over the surface to be cleaned. In the present instance the latch means is shown as comprising a latch nose 10 attached to a spring strip 11 intermediate between the ends of the strip. Strip 11 is located inside wand 8 adjacent to the end of the wand and at one end is attached to the wand by suitable means, such as rivets, as is indicated at 12. The other end of strip 11 is provided with a latch releasing button 13 which projects out through an opening in the wand and is biased to such position by the inherent resiliency of spring strip 11. Latch nose 10 also projects out through an opening in the wand and is biased to such position by the spring strip. With such a latch structure each cleaning tool is provided with a sleeve into which the wand end may be inserted, the sleeve having walls which form an annular groove in which latch nose 10 engages when the wand end is inserted into the sleeve to lock the cleaning tool on the wand end. As shown in Fig. 6, the one side of nose 10 is rounded as is indicated at 14 whereby when the wand end is inserted into the tool sleeve it will be forced inward by being pressed against the end of the sleeve; and when in line with the annular groove in the sleeve will spring out into it thus fastening the cleaning tool to the wand. The locking means may be released to permit removal of a cleaning tool by pressing inward on button 13.

The vacuum cleaner structure so far described is a known one and is to be taken as typical of such structures. Our invention has to do with providing means whereby the end of the wand may be attached to the vacuum cleaner casing whereby the wand may be used

as a handle for moving the cleaner over a floor, from room to room, or up and down stairs, and also providing means whereby the cleaner may be stored against a wall. It should be understood that in accomplishing this, it is contemplated that the wand and flexible section may be simultaneously connected to the cleaner, when using the wand as a handle, or that the wand may be disconnected from the flexible section, connected to the cleaner, and used alone to push the cleaner around.

Attached to the wall of casing 1 by suitable means is a transversely extending escutcheon plate 16 formed integral with which is a boss 17 having an opening which forms the suction inlet 4, such opening being in alignment with an opening in the casing 1. Also integral with escutcheon plate 16, and extending longitudinally thereof adjacent to inlet 4 is an outwardly projecting ledge 18 which forms a handle for the cleaner for use in lifting and carrying it, the ledge being provided with an opening 19 through which a hand may be passed. Beneath ledge or handle 18 between its underside and boss 17 are walls which form a pocket 20 in which the tool end of wand 8 may be inserted. A portion of the top wall of pocket 20 is defined by a curved wall 21 on the underside of handle 18 and in such curved wall is a locking groove 22, adapted to receive latch nose 10. As shown in Fig. 5, locking groove 22 extends throughout the extent of curved pocket wall 21 so that it is open at its ends; and by this arrangement locking nose 10 may be moved out of the groove by turning wand 8 in either direction.

To attach the wand to the cleaner casing it is necessary merely to push the end of the wand into the pocket as shown in Fig. 6. As the wand end is pushed into the pocket, latch nose 10 will be forced inward by reason of rounded surface 14 and will ride along the inner surface of the pocket until it comes in line with groove 22 whereupon it will snap out into the groove thus locking the wand end in the pocket. The wand end may be removed from the pocket by merely twisting or turning the wand in either direction to move the latch nose out of groove 22 and then pulling the wand end out of the pocket. This is an advantageous feature of the invention since no stooping to release the latch nose by pushing in on button 13 is required.

An important feature of our invention resides in providing the ledge which forms the handle adjacent to the suction inlet and then locating the pocket for attachment of the tool end of the wand to the casing beneath the ledge between its underside and the suction inlet, the pocket being formed partly by a surface on the underside of the handle which surface is provided with the locking groove for the wand latch. This forms a simple compact structure which can be provided at low cost and one to which the tool end of the wand can be quickly and easily attached and from which it can be detached with a minimum of effort.

When the wand is locked in the pocket, flexible hose section 5 and wand 8 form a loop as shown in Figs. 1, 2 and 3, the flexible section hanging draped under the wand. Thus the flexible section is fairly out of the way and does not interfere with moving the cleaner casing about on its wheels as illustrated by Figs. 2 and 3. This is especially important when moving the cleaner up or down stairs as shown particularly in Fig. 3 since by having the wand connection adjacent to the hose connection, the flexible section does not contact with the steps. Also the loop may be used to great advantage in storing the cleaner, the loop being positioned over a hook H located at a suitable height on a wall W as shown in Fig. 1. In Figs. 1 and 2, F indicates a floor.

The invention utilizes the latch means already provided on the wand end for connecting cleaning tools to it as the latch means for connecting the wand end to the cleaner casing. Accordingly, to embody the invention in a vacuum cleaner it is necessary merely to provide the ledge 18 which forms the handle and the additional walls

between its underside and the suction inlet needed to form the pocket, a thing which involves little additional cost especially since a handle is required anyway.

The broad idea of a wheeled vacuum cleaner including a pocket for the reception of the tool contacting end of a wand to thereby provide a rigid handle to move the cleaner on its wheels from one place to another is not our invention, but is described and claimed in the application of James P. Hunter, Serial No. 399,270, filed con-

10 currently with this application and assigned to the assignee of the present application.

What we claim as new and desire to secure by Letters Patent of the United States is:

1. A vacuum cleaner comprising a casing having a suction inlet, wheels on the casing for supporting it and on which it may be moved; a suction hose comprising a flexible section and a rigid wand section, the end of the wand section being provided with latch means for connection of cleaning tools thereto, means connecting the end of the flexible section to the suction inlet, a handle forming ledge adjacent to the said suction inlet, and walls including a wall portion which is a part of said handle forming ledge which define a pocket into which the end of the wand section may be positioned, said pocket forming walls comprising latch means for engagement by the tool latching means at the end of the wand section for fastening the wand section in the pocket.

2. The combination defined by claim 1 wherein the tool latching means comprises a locking nose and the pocket latching means comprises an open ended groove in the handle forming ledge whereby the tool latching means may be released by turning the wand end in the pocket.

3. A vacuum cleaner comprising a casing, wheels on the casing for supporting it and on which it may be moved, walls on the casing which define a suction inlet to which the end of the flexible section of a suction hose may be connected, a handle forming ledge on the casing adjacent to said suction inlet, and walls including a wall portion which is a part of said handle forming ledge which form a pocket located between the suction inlet and the ledge in which the end of a wand section of a suction hose may be connected, said pocket forming walls comprising latch means with which cleaning tool latch means on the wand section end may engage.

4. The combination defined by claim 3 wherein the latch means in the pocket forming walls comprises an open ended groove in the handle forming ledge for co-operation with a wand section latch in the form of a spring pressed latch nose.

5. A vacuum cleaner comprising a casing having a suction inlet, wheels on opposite ends of the casing for supporting it and on which it may be moved, a suction hose comprising a flexible section and a rigid wand section, the end of the wand section being provided with latch means for connection of cleaning tools thereto, means connecting the end of the flexible section to the suction inlet, a handle forming ledge adjacent to the said suction inlet, and walls including a wall portion which is a part of said handle forming ledge which define a pocket into which the end of the wand section may be positioned, said pocket forming walls comprising latch means for engagement by the tool latching means at the end of the wand section for fastening the wand section in the pocket.
